MACHINE FOR FASTENING UPPERS
TO INSOLESEdward Quinn, Saugus, Mass., assignor to United
Shoe Machinery Corporation, Flemington, N. J.,
a corporation of New Jersey

Application January 25, 1944, Serial No. 519,623

9 Claims. (Cl. 12—14)

This invention relates to machines for fastening uppers to insoles, and more particularly to machines for thus operating on the heel-end portions of uppers. The invention is herein illustrated as applied to a machine of a well-known type commonly used for lasting the heel ends of shoes, an object being to adapt such a machine for convenient and successful use for the purpose of fastening to the heel ends of insoles the previously molded heel parts of the uppers of so-called two-part sandals. It should be understood, however, that the invention is not limited to machines of that particular type nor limited in utility to the manufacture of footwear of that particular kind.

A machine of the above-mentioned type is provided with wipers which in the usual operation of lasting the heel end of a shoe wipe the margin of the upper inwardly over an insole on the last, with a heel band for embracing the upper about the heel end of the last and for clamping it against the end and side faces of the last, with devices for inserting fastenings to fasten the overwiped margin of the upper to the insole, and with a work support or jack which is swung rearwardly from an initial forwardly inclined position to present the work to the operating instrumentalities. After such a work-presenting movement of the work support the heel band is closed about the heel end of the upper, the wipers are operated to wipe the margin of the upper inwardly over the insole and the fastening-inserting devices are then operated to drive the fastenings. To adapt such a machine better for use to fasten the molded heel parts of the uppers of two-part sandals to insoles, the construction herein shown includes clamps carried by the work support and arranged to engage and to clamp against the side faces of the heel end of a last portions of such a molded heel part which are embraced by the heel band and are further subjected to clamping pressure by the band. Novel mechanism also mounted on the work support is movable by the operator to apply the clamps to the molded heel part while the work support is in its initial forwardly inclined position. Accordingly, the clamps serve to maintain the heel part in proper relation to the last and the insole during the work-presenting movement of the work support, which the operator could not conveniently do with his fingers. In a machine of the type shown, moreover, they assist in counteracting a tendency which the heel band has, by its engagement with the rear end face of the molded heel part only in a loca-

tion comparatively near the bottom of the last, to tip the front ends of the heel part in downward directions. To render the clamps especially effective for this purpose, they are made resiliently flexible and are so formed and arranged that as they are forced against the heel part they are flexed and thereby tend frictionally to work the side portions of the heel part heightwise of the last toward the edge of the insole.

10 The clamps may thus be flexed to some extent when they are initially applied to the heel part by the operator, and they are thereafter further flexed by the pressure of the heel band against them when the latter is closed about the heel end 15 of the last and has its greatest tendency to depress the front ends of the heel part by its pressure on the rear end face thereof. The clamps accordingly serve to prevent any such objectionable displacement of the heel part before it is secured to the insole. Their use for this purpose is especially advantageous when, as herein illustrated, the earlier molding of the heel part has been such as to conform it only to the contour of the end and side faces of the last, its 20 marginal portion which is to overlie the insole not having as yet been molded to provide a flange parallel to the bottom face of the insole. It will be understood that in operating on a heel part prepared in this manner the wipers of the machine herein shown wipe its marginal portion over the insole after the heel part has been clamped about the heel end of the last as above described.

25 The above and other features of the invention, including various novel details of construction and combinations of parts, will now be more particularly described with reference to the accompanying drawings and thereafter pointed out in the claims.

30 In the drawings, Fig. 1 is a view partly in right-hand side elevation and partly in section of a portion of a machine of the previously mentioned type having the present invention applied thereto, the parts of the machine being shown in the positions which they occupy immediately prior to the driving of the fastenings;

35 Fig. 2 is a view similar to Fig. 1 of a portion of the structure there shown, but with the parts positioned as they appear prior to the starting of the power operation of the machine and when the work support has received a portion only of its work-presenting movement;

40 Fig. 3 is a vertical sectional view illustrating the relation of one of the clamps provided by

this invention to the heel band and to the molded heel part of the upper before the heel band is fully closed;

Fig. 4 is a view similar to Fig. 3, but showing the parts as they appear after the closing of the heel band;

Fig. 5 is a view substantially in front elevation of the clamping means as initially positioned on the work support;

Fig. 6 is a view similar to Fig. 5, showing the clamping means in clamping relation to the heel part of the upper prior to the work-presenting movement of the work support;

Fig. 7 is a perspective view of the molded heel part before it is assembled with an insole; and

Fig. 8 shows the heel part after it has been fastened to the insole on a last by the use of this machine.

The machine to which the invention is herein illustrated as applied is a machine of the type disclosed in United States Letters Patent No. 1,583,044, granted on May 4, 1926, on an application of C. H. Hoyt's, but modified in some respects as further disclosed in Letters Patent No. 1,558,737, granted on October 27, 1925, on an application of R. F. McFeely's and Letters Patent No. 1,852,015, granted on April 5, 1932, on an application of J. C. Jorgensen. Such a machine, which is commonly used for lasting the heel ends of shoes, includes a heel band 2 for embracing and clamping an upper about the heel end of a last, a pair of wipers 4 (only one of which is herein shown) for wiping the margin of the heel end of the upper inwardly over an insole on the last, and upper-fastening means comprising a plurality of tack drivers 6 movable downwardly to drive a row of tacks through openings in the wipers to fasten the overwiped margin of the upper to the insole, the construction of the upper-fastening means and its relation to the wipers being disclosed particularly in the above-mentioned Letters Patent No. 1,852,015. The work is mounted on a work support or jack 8 which is mounted at its lower end on a shaft 10 for swinging movement from an initial forwardly inclined work-receiving position to carry the last and its shoe materials rearwardly toward the heel band 2, the work support including a post 12 movable upwardly and downwardly and provided at its upper end with a pin 14 arranged to enter the usual spindle hole in the heel end of the last. Fast on the post 12 is a forwardly extending arm 16 which serves as a support for a toe rest 18 under the toe end of the last. Before starting the power operation of the machine the operator swings the work support rearwardly to carry the heel-end face of the upper into engagement with the heel band and also imparts upward movement to the post 12 to carry the heel end of the insole into engagement with a cam-controlled holdown 20 which determines the position of the work heightwise relatively to the wipers 4. Such upward movement of the post 12 is effected by means of a treadle 22 connected by a link 24 to a lever 26 pivotally mounted on the lower end of the work support, the front end of this lever underlying the lower end of a rack bar 28 through which the post 12 is raised. After the starting of the power operation of the machine the work support is controlled automatically by mechanism constructed substantially as disclosed in Letters Patent No. 1,558,737. This mechanism includes a cam-operated slide 30 arranged to impart swinging movement in a clockwise direction (Fig. 1) to a bell-crank lever 32 connected by a link 34 to pawl-and-ratchet mech-

anism 36 which acts on the work support through a pinion 38 and a rack bar 40 to force the heel end of the upper more firmly against the heel band 2. The bell-crank lever 32 is yieldingly connected by another link 42 to pawl-and-ratchet mechanism 44 through which a pinion 46 on the shaft 10 is operated to urge the rack bar 28 upwardly and thus to force the work more firmly up against the holdown 20. Through mechanism not herein fully shown the slide 30 serves also to close the heel band inwardly against the sides of the heel end of the upper. For a more complete understanding of the construction thus far described and of the manner of operation of a machine of the type herein shown the previously mentioned Letters Patent may be consulted.

The present invention has especially, although not exclusively, in view, the use of a machine of the above-mentioned type for the purpose of fastening to the heel end of an insole mounted on a last or other form the previously molded heel part of the upper of a so-called two-part sandal. Such a molded heel part is shown at *a* in Fig. 7, and may be produced, for example, by a molding machine such as shown in United States Letters Patent No. 2,266,774, granted on December 23, 1941, on an application of A. A. Lawson. It is shaped to conform substantially to the contour of the end and side faces of the heel-end portion of a last of the corresponding style and size, but as illustrated the marginal portion *b* thereof which is to overlie the insole is not fully molded to lie flat on the insole, but is only inclined inwardly and crimped in a preliminary manner along the curved rear portion of the heel part. It will be evident that a machine of the type herein shown is adapted to position and hold such a molded heel part in proper relation to the heel end of a last and to the heel end of an insole on the last by means of its heel band, to wipe the marginal portion of the heel part into parallel relation to the bottom of the insole and to fasten the overwiped margin to the insole. It is, however, inconvenient, if not impossible, for the operator, after mounting the molded heel part on the heel end of the last, to hold it with his fingers in proper relation to the last and the insole during the work-presenting movement of the work support and until the heel part is clamped and held by the heel band. For purposes of this invention, therefore, the machine herein shown is provided, on the work support, with a pair of clamps 48 arranged to clamp the forward portions of the heel part against the sides of the heel end of the last. Each of these clamps comprises a resiliently flexible metal plate 50 which is somewhat curved or bowed heightwise of the last with its concave side toward the last and is pivotally mounted at its lower end on a pin 52 supported in a plate 54 which is fast on a block 56 secured by clamping screws 58 to the forwardly extending work support arm 16. Upon loosening these screws the block with the parts thereon may be adjusted in directions lengthwise of the last. The upper end portion of each plate 50 extends in a rearward direction relatively to the rest of the plate and has mounted thereon a cover 60 of cloth or other suitable material for engaging the heel part. For swinging the clamps 48 inwardly into clamping relation to the heel part from the initial positions in which they are shown in Fig. 5, the machine is provided with a pair of levers 62 arranged in toggle-like relation to each other and pivotally connected together at their inner ends by a stud 64. These levers are fulcrumed between their opposite ends on studs 66 which are threaded

in a plate 61 fast on the block 56 and extend through slots 68 in the levers to permit the latter to shift lengthwise in their toggle-like movement. The outer ends of the levers 62 are pivotally connected to the lower ends of links 70 the upper ends of which are pivotally connected to blocks 72 fastened to the plates 50 in locations below the work-engaging portions of the clamps 48. It will thus be seen that in response to swinging movements of the levers 62 from the positions in which they are shown in Fig. 5 to positions such as illustrated in Fig. 6 the clamps are swung inwardly into clamping relation to the molded heel part. For thus swinging the levers 62 there is pivotally mounted on a stud 14 on the plate 61 a hand lever 76 connected by a link 78 to the stud 64 connecting the inner ends of the levers. For holding the clamps in their clamping positions there is pivotally mounted on the hand lever 76 a pawl 80 arranged to engage ratchet teeth 82 on the plate 61. The pawl is held normally against the ratchet teeth by a spring 84. To release it from the ratchet teeth and permit the clamps to be returned to their initial positions there is pivotally mounted on the hand lever 76 a small lever 86 connected to a tail on the pawl.

By reference to Fig. 1 it will be seen that the heel band 2, formed as usual in machines of the type herein shown, engages the rear end face of the molded heel part only in a location comparatively near the bottom of the last, and by such engagement it has some tendency to tip the heel part in the direction to depress its front end portions, especially when the heel band is closing and the work is being forced more firmly back against the band through the pawl-and-ratchet mechanism 36. The clamps 48, by clamping the heel part against the sides of the heel end of the last, help to maintain it in proper position against any such tendency of the heel band to displace it. They are, moreover, so formed that they engage the heel part initially in locations comparatively near the edge of the last bottom, as will be evident from Fig. 6 where their lower work-engaging portions are still spaced from the heel part, and as they are applied by the mechanism shown in Figs. 5 and 6 the curved, resilient plates 50 may be partially straightened, so that the work-engaging portions of the clamps tend by frictional engagement with the heel part to work its front end portions upwardly. In view, moreover, of the fact that the work-engaging portions of the clamps are located between the heel part and the heel band and are subjected to pressure by the heel band when the latter is closed inwardly toward the sides of the last in the power operation of the machine, the force applied to the clamps by the heel band has a further tendency to flex them with a frictional action in an upward direction on the sides of the heel part, as will be evident from a comparison of Figs. 3 and 4. Compensation is thus afforded for such tendency as the heel band has to displace the heel part at the time when the band applies its greatest pressure to the rear end face thereof.

In the use of the machine for the purpose described the operator mounts on the work support while it is in its initial forwardly inclined position a last having an insole c fastened as usual by tacks on its bottom face. He then mounts on the heel end of the last a molded heel part a formed, for example, as illustrated in Fig. 7, and by downward movement of the hand lever 76 swings the clamps 48 inwardly to clamp the forward portions of the heel part against the sides

of the heel end of the last, as illustrated in Fig. 6. In this operation the clamps engage the heel part first in locations comparatively near the edge of the last bottom, and the curved resilient plates 50 of the clamps may be sprung somewhat inwardly by the force applied to the hand lever, so that the work-engaging portions of the clamps tend frictionally to work the front end portions of the heel part in an upward direction. Thereafter the operator swings the work support rearwardly to carry the rear end face of the molded heel part into engagement with the heel band 2, and by depression of the treadle 22 imparts upward movement to the post 12 to bring the heel end of the insole into engagement with the holdown 20. During this work-presenting movement of the work support the clamps 48 maintain the molded heel part in proper relation to the last.

After the work has thus been presented the operator starts the power operation of the machine. Near the beginning of its operation the work support is acted upon through the pawl-and-ratchet mechanism 36 to cause the heel band to press firmly on the heel-end face of the molded heel part and the work also is forced more firmly up against the holdown 20 through the pawl-and-ratchet mechanism 44. At substantially the same time the heel band is closed about the heel end of the last. The cam which controls the holdown 20 may, if desired, be so formed as to omit the usual short work-depressing movement of the holdown at this time. As the heel band is closed it presses inwardly against the clamps 48 and by its pressure on the clamps flexes them additionally to bring them into pressing engagement with the heel part in locations still farther from the edge of the last bottom, as will be evident from Figs. 3 and 4. The clamps thus have a further tendency at this time to work the forward portions of the heel part upwardly. This action of the clamps, supplementing their earlier similar action on the heel part in response to the movement of the hand lever 76, compensates effectively for such tendency as the heel band has to depress the front ends of the heel part by its pressure on the rear-end face thereof. After the closing of the heel band the wipers 4 are moved inwardly and wipe the marginal portion of the heel part over the insole. As usual in machines of the type shown the wipers are then retracted and moved inwardly again, the holdown 20 being lifted slightly to cause the wipers in their second inward movement to wipe the margin of the heel part more firmly down on the insole. The tack drivers 6 are then operated to drive the tacks t (Fig. 8) for fastening the heel part to the insole. After the driving of the tacks the wipers are retracted and the other parts of the machine are returned to their starting positions, the work support being released to permit it to swing forwardly and to permit downward return movement of the post 12. Thereafter the operator disengages the pawl 80 from the ratchet teeth 82, moves the hand lever 76 upwardly to withdraw the clamps 48 from the work, and removes the work from the machine.

In the appended claims the term "form" is used generically to refer to a last such as herein shown or to any other kind of form on which the shoe parts may be mounted for the purposes in view. Since it is contemplated, moreover, that a machine provided with clamping means such as herein shown may be used, if desired, to fasten the heel-end portion of a full-length upper to an insole under any conditions which may render

such use desirable, the term "heel part" as used in the claims is not intended, unless required by the context, to be limited to a heel part which is formed as a unit separate from other portions of the upper.

Having described the invention, what I claim as new and desire to secure by Letters Patent of the United States is:

1. In a machine for fastening the heel parts of uppers to insoles, the combination with upper-fastening means, of a support for a form having thereon an insole and the heel part of an upper to be fastened to the insole, said support being mounted for work-presenting movement from an initial work-receiving position, clamps carried by said support for clamping the heel part of the upper against the sides of the form, said clamps being pivotally mounted for swinging movements about axes extending lengthwise of the form, a pair of levers fulcrumed between their ends on said support and pivotally connected together in a toggle-like relation to each other, said levers being connected to the clamps in locations between the axes and the work-engaging portions of the clamps for swinging the latter into their clamping positions, and means for swinging said levers thus to operate the clamps.

2. In a machine for fastening the heel parts of uppers to insoles, the combination with upper-fastening means, of a support for a form having thereon an insole and the heel part of an upper to be fastened to the insole, said support being mounted for work-presenting movement from an initial work-receiving position, clamps carried by said support for clamping the heel part of the upper against the sides of the form, said clamps being pivotally mounted for swinging movements about axes extending lengthwise of the form, a pair of levers also carried by said support and connected together in a toggle-like relation to each other, members on which said levers are fulcrumed between their opposite ends and relatively to which they are shiftable lengthwise in their toggle-like movement, and means positively connecting said levers to the clamps for swinging said clamps into their clamping positions by the swinging of the levers about said members.

3. In a machine for fastening the heel parts of uppers to insoles, the combination with upper-fastening means, of a support for a form having thereon an insole and the heel part of an upper to be fastened to the insole, said support being mounted for work-presenting movement from an initial work-receiving position, resiliently flexible clamps carried by said support for clamping the heel part of the upper against the sides of the form, said clamps being pivotally mounted for swinging movements about axes extending lengthwise of the form, a pair of levers also carried by said support and having a toggle-like relation to each other, said levers being fulcrumed to swing about axes between their opposite ends in their toggle-like movement, and links connecting said levers respectively to the different clamps in locations between the axes and the work-engaging portions of the clamps for swinging the latter into their clamping positions by the swinging of the levers.

4. In a machine for fastening the heel parts of uppers to insoles, the combination with upper-fastening means, of a support for a form having thereon an insole and the heel part of an upper to be fastened to the insole, said support being mounted for work-presenting movement from an initial work-receiving position, clamps carried by

said support for clamping the heel part of the upper against the sides of the form, said clamps being pivotally mounted for swinging movements about axes extending lengthwise of the form, a pair of levers also carried by said support and having a toggle-like relation to each other, said levers being fulcrumed to swing about axes between their opposite ends in their toggle-like movement and being connected respectively to the different clamps in locations between the axes and the work-engaging portions of the clamps for swinging the latter into their clamping positions by the swinging of the levers, another lever carried by said support, and a link connecting said other lever to the pair of levers for operating the latter.

5. In a machine for fastening the heel parts of uppers to insoles, the combination with upper-fastening means, of a support for a form having thereon an insole and the heel part of an upper to be fastened to the insole, a heel band for embracing the heel part of the upper about the form and for clamping it against the end and side faces of the form, and additional means for engaging and clamping against the side faces only of the form portions of said heel part which are thus embraced and clamped by the heel band, said additional means being arranged to have a frictional action on the portions thus engaged tending to work them heightwise of the form toward the edge of the insole.

6. In a machine for fastening the heel parts of uppers to insoles, the combination with upper-fastening means, of a support for a form having thereon an insole and the heel part of an upper to be fastened to the insole, a heel band for embracing the heel part of the upper about the form and for clamping it against the end and side faces of the form, and clamps arranged to engage and to clamp against the side faces only of the form portions of said heel part which are thus embraced and clamped by the heel band, said clamps being flexibly movable with a frictional action on the portions thus engaged tending to work them heightwise of the form toward the edge of the insole as the clamping pressure is applied.

7. In a machine for fastening the heel parts of uppers to insoles, the combination with upper-fastening means, of a support for a form having thereon an insole and the heel part of an upper to be fastened to the insole, a heel band for embracing the heel part of the upper about the form and for clamping it against the end and side faces of the form, and clamps arranged to engage and to clamp against the side faces only of the form portions of said heel part which are located between the form and the heel band, said clamps being movable in response to pressure of the heel band thereon with a frictional action on the portions thus engaged tending to work them heightwise of the form toward the edge of the insole.

8. In a machine for fastening the heel parts of uppers to insoles, the combination with upper-fastening means, of a support for a form having thereon an insole and the heel part of an upper to be fastened to the insole, a heel band for embracing the heel part of the upper about the form and for clamping it against the end and side faces of the form, and resiliently flexible clamps for engaging and clamping against the side faces only of the form portions of said heel part which are thus embraced by the heel band, said clamps being arranged to be flexed by the

pressure of the heel band thereon with a frictional action on the sides of the heel part tending to work them heightwise of the form toward the edge of the insole.

9. In a machine for fastening the heel parts of uppers to insoles, the combination with upper-fastening means of a support for a form having thereon an insole and the heel part of an upper to be fastened to the insole, a heel band for embracing the heel part of the upper about the form and for clamping it against the end and side faces of the form, resiliently flexible clamps

5 for engaging and clamping against the side faces only of the form portions of said heel part which are thus embraced by the heel band, and means for applying said clamps in clamping relation to the heel part prior to the clamping action of the heel band, said clamps when thus applied being arranged to be flexed with a frictional action on the sides of the heel part tending to work them heightwise of the form toward the edge of the insole and thereafter to be further similarly flexed by pressure of the heel band thereon.

EDWARD QUINN.
